UNITED STATES PATENT OFFICE.

MARTIN FALL, OF JOHNSTOWN, PENNSYLVANIA.

FURNACE-BURNER.

964,902.

Specification of Letters Patent. Patented July 19, 1910.

Application filed May 20, 1909. Serial No. 497,280.

To all whom it may concern:

Be it known that I, MARTIN FALL, a citizen of the United States, residing at Johnstown, in the county of Cambria and State 5 of Pennsylvania, have invented a new and useful Furnace-Burner, of which the following is a specification.

This invention is a burner for use within a heating furnace whereby natural gas or 10 similar fuel may be utilized to heat a dwelling either through hot air, hot water or steam heating systems.

One object of the invention is to provide a burner of simple construction by which 15 the heat will be confined along the sides of the furnace, and loss of the same by the heating of surfaces which will perform no part in the heating of the dwelling will be avoided.

20 A further object of the invention is to provide a burner in which the entrance of cold air to the combustion chamber will be reduced to a minimum so that the heat generated will be fully and efficiently utilized.

25 A further object of the invention is to provide a device of simple construction by which the burner jets will be kept free of accumulation of soot or other deposits at 30 all times.

With these and such other objects as will hereinafter incidentally appear, in view, the invention consists in certain novel features of the device illustrated in the accompanying 35 drawings, all of which will be herein-after fully described and subsequently pointed out in the claims.

In the accompanying drawings, Figure 1 is a view showing my improved burner in 40 elevation, a portion of a furnace being indicated in dotted lines so as to illustrate the use of the burner. Fig. 2 is an enlarged vertical section of a portion of the burner.

45 In carrying out my invention, I employ an annular burner body 1 which may be of any desired size according to the requirements of any particular place, and is preferably constructed in sections bolted together through registering lugs 2, as shown in Fig. 1. The gas or other fuel is supplied to the burner from a supply pipe 3, which leads into the under side of the body 1, and in its upper side the burner body is provided with jet orifices 4 through which the 50 fuel passes to be ignited and consumed.

Adjacent each of the jet orifices 4 on the upper side of the burner body I provide deflecting plates or hoods 5 which serve to protect the jets from falling soot or other material so that the flame may be constant 60 and the fuel may burn freely at all times. On the inner circumference of the annular burner body I provide the inwardly projecting lugs 6 which support a holder 7, and a deflector 8. The holder 7 is in the form 65 of a cylindrical body having a plurality of perforations 9 in its upper portion and provided near its lower end with a series of outwardly projecting radial lugs or supports 10 upon which a mass of refractory material, such as asbestos, fire clay or slag, indicated at 11, may be supported so as to retard the flow of the flame and diffuse the 70 heat in the usual manner. On its inner side, near its lower end, the holder is provided with an internal annular flange or rim 12 which is adapted to rest upon the lugs 6 and thereby support the holder in its proper position and also receive and support the lower end of the deflector, as 75 clearly shown in Fig. 2. The said deflector 8 is a cylindrical formation, and is provided with a closed lower end, as indicated at 13, and at its lower end has an outstanding annular flange or shoulder 14 which is 80 adapted to rest on the internal flange or rim 12 of the holder and thereby support the deflector in its proper position. This deflector 8 may be of any size according to the size of the furnace and is constructed 85 in sections, as indicated at 15, whereby it may be extended to any height within the furnace as may be necessary. The deflector serves to confine the flame along the side walls of the furnace so that there is no 90 waste of fuel due to a concentration of the flame at the center of the combustion chamber which would mean a loss of valuable heat units. The deflector may be constructed of any suitable material such as 95 asbestos, fire clay or sheet metal. I prefer to employ sheet metal owing to its lightness and the ease with which it may be handled and its low cost.

100 It is thought the advantages of my improved device will be readily understood from the foregoing description, taken in connection with the accompanying drawings. The fuel is supplied to the burner body and is ignited at the jet orifices in the 105 110

usual manner so as to produce a flame which will tend to rise from the space between the holder and the side of the fire box of the furnace. The fire balls or refractory material placed in this space above the lugs or brackets 10 will become incandescent and thereby throw out a great volume of heat so that the dwelling may be quickly raised to and easily maintained at the desired 10 temperature. The deflectors 5 effectually prevent the impurities, due to imperfect combustion, from falling upon and clogging the jet orifices while the lugs or brackets 10 will effectually support the material 11 and 15 prevent the same from dropping upon the burner jets. Sufficient air to support combustion will find its way through the openings 9 in the holder and around the burner body but the flow of a great volume of cold 20 air upward through the furnace will be positively prevented by the imperforate bottom 13 of the deflector 8.

The device is of a very simple and cheap construction and is efficient in operation.

25 While I have referred to the device as annular and cylindrical, it is not to be understood that the invention is confined to use in furnaces of a round form as it may be employed in furnaces which have a 30 square or any other horizontal outline.

Having thus described my invention, what I claim is:—

1. The combination with an annular burner body, of inwardly projecting lugs on 35 the said body, and a cylindrical deflector resting upon the said lugs and having an imperforate bottom.

2. The combination with an annular burner body having inwardly projecting 40 lugs, of a cylindrical sectional deflector

provided at its lower end with an annular flange resting on the said lugs.

3. The combination with an annular burner body having jet openings in its upper side, of a holder supported by and upon the burner body concentric with the inner wall thereof and provided with outstanding supports near its lower end on its outer side projecting over the burner body, and refractory incandescing material resting on 50 said supports directly over the burner body in the path of a flame from the jet openings in the upper side of the same.

4. The combination with an annular burner body, of a cylindrical deflector supported by and upon the inner wall thereof, and a holder supported by the burner body concentric with and between the said body and the deflector and provided with outstanding projections adapted to support a 60 refractory material over the burner body.

5. The combination with a burner body having inwardly projecting lugs, of a holder provided at its lower end with an internal flange resting on said lugs and provided 65 with outstanding supports.

6. The combination with a burner body, of a holder supported by and above the burner body and provided with a series of openings through its upper portion and 70 having outstanding supports near its lower end.

In testimony that I claim the foregoing as my own, I have hereto affixed my signature in the presence of two witnesses.

MARTIN FALL.
